UNITED STATES PATENT OFFICE.

JOSEPH R. CRABILL, OF LA HARPE, ILLINOIS.

STEAM-BOILER.

SPECIFICATION forming part of Letters Patent No. 650,598, dated May 29, 1900.

Application filed January 29, 1900. Serial No. 3,250. (No model.)

To all whom it may concern:

Be it known that I, JOSEPH R. CRABILL, a citizen of the United States, residing at La Harpe, county of Hancock, State of Illinois, 5 have invented a new and useful Improvement in Steam-Boilers, of which the following is a specification.

My invention relates to the separation of dry steam from the water in a steam-boiler 10 when generating and delivering the steam rapidly for use.

My invention consists of a system of one or more suitably-shaped pipes or passage-ways for steam from parts of the generator that are 15 distant from the dome to the upper interior part of the dome, in addition to the usual passage-way through the base of the dome, furnishing free passage-way for steam through any water that may be in the way from any 20 cause.

The objects of my invention are to prevent priming and foaming and to furnish dry steam to the upper part of the dome of boiler when steam is rapidly drawn or escapes from it for 25 use or relief; also, allowing water-line to be carried higher under similar conditions, thereby raising the factor of safety; also, preventing water from working over from waves and sloshing in generator of traction-engines when 30 operating on rough roads. I attain these objects by mechanism illustrated in the accompanying drawings, in which—

Figure 1 is a sectional elevation of the upper part of a steam-boiler with my device in 35 place. Fig. 2 is a perspective view of one of the pipes of my devices, shown separately.

Similar letters of reference refer to similar parts throughout both views.

In reference to the drawings, A shows the 40 interior of a steam-boiler, with dome B. The dotted line E is the water-line, with steam-space S above it.

C and D are L-shaped pipes or passage-ways for steam, having free opening through 45 them, with one end opening into steam-space S in part of boiler A that is distant from the dome B and the other end opening into the upper part K of the dome B, and they are in no way connected with the steam-pipe F, 50 which conveys steam from the boiler A. The usual opening from the generating part of the boiler A into the base of the dome B is not

closed or constricted in any way by the passages C and D.

In the operation of my improvement I use 55 two passage-ways C and D; but other numbers can be used to advantage in some of the forms of steam-generating boilers. The steam-pipes and passage-ways C and D should be large enough for either of them, regardless of 60 number, to furnish a free and ample passage-way for a volume of steam equal to the entire output of the generator, but are only called on to act as such passages in any sensible degree when conditions arise that are herein- 65 after described.

The operation of my invention in supplying steam into the top of the dome B when the capacity of the generator A is drawn on heavily through and by the steam-pipe F can 70 be best understood by what takes place in a steam-generator when foaming and priming are in progress. I find by observing the illuminated interior of a steam-generator when foaming and priming progresses and the 75 steam is drawn rapidly from the dome that at first there is a foaming and frothing on the surface of the water. Then a cone of foaming water forms and begins to rise directly under the dome and continues to rise until it 80 reaches the base of the dome and shuts off or obstructs the dry steam in its passage from the distant end of the generator to the top of the dome. The dry steam in the end of the generator by its rapid generation and expansion forces the water and foam in and near the base of the dome upward and delivers it into the steam-pipe F. When water is thus 85 raised in any part of a steam-generator, it is correspondingly lowered in other parts. 90

In operating a steam-generator embodying and embracing my device the steam passage-ways C and D furnish free and unobstructed passages for dry steam from the parts of the generator which are distant from the dome to 95 the upper part of the dome through any water or foam that may intervene from any cause.

My device is self-operative and will instantly, at any and all times, deliver the 100 driest steam from where the water is the lowest in a generator to the upper part of the dome B, from which it is drawn by the steam-pipe F for use.

My device has no moving parts and requires no ulterior force to cause it to act, but depends on the different weights of dry steam, wet steam, foam, and water to operate it.

- 5 I do not confine myself in the application of my device to any form of steam-generator or any specific form of dome, and my device is just as effective when the steam-chest of an engine is made to act as a dome. Nor do
10 I contemplate the use of any particular shape of pipes or passage-ways C and D, except they have no opening into them for the passage of steam other than at their ends. Any shaped pipe, however formed, or any form of
15 cross-section may be used.

Having thus fully described my invention,

what I claim, and desire to secure by Letters Patent, is—

In a steam-generator, the combination with the steam-dome, open-ended pipes forming 20 collectors, extending from the upper interior of said dome to distant parts of the generator above the water-line thereof, whereby steam may be collected and delivered into said dome in addition to the ordinary open 25 bottom thereof, and foaming is prevented, as and for the purpose described.

JOSEPH R. CRABILL.
